US00D944918S

(12) **United States Design Patent** (10) Patent No.: **US D944,918 S**
 Jurczyszak et al. (45) Date of Patent: ** Mar. 1, 2022

(54) **FAUCET STEAM SHIELD**

(71) Applicant: **Rheem Manufacturing Company**, Atlanta, GA (US)
 (72) Inventors: **Eric R. Jurczyszak**, Waterbury, CT (US); **Sergiu G. Mihu**, Waterbury, CT (US); **Christopher M. Hayden**, Waterbury, CT (US); **Lejsan Jusufi**, Waterbury, CT (US)

(73) Assignee: **Rheem Manufacturing Company**, Atlanta, GA (US)

(**) Term: **15 Years**

(21) Appl. No.: **29/650,080**

(22) Filed: **Jun. 4, 2018**

(51) LOC (13) Cl. **23-01**
 (52) U.S. Cl.
 USPC **D23/213**

(57) **CLAIM**

The ornamental design for a faucet steam shield, as shown and described.

DESCRIPTION

FIG. 1 is a top perspective view of our new design for a faucet steam shield;

FIG. 2 is a bottom perspective view thereof;

FIG. 3 is a right side elevation view thereof;

FIG. 4 is a left side elevation view thereof;

FIG. 5 is a front elevation view thereof;

FIG. 6 is a back elevation view thereof;

FIG. 7 is a top plan view thereof; and,

FIG. 8 is a bottom view thereof.

The broken lines showing in FIGS. 1, 3-7 represent environment and the broken lines in FIGS. 2 & 8 represent portion of a faucet steam shield and environment and form no part of the claimed design.

1 Claim, 6 Drawing Sheets
